UNITED STATES PATENT OFFICE.

PIERRE A. RONTEY, OF COSCOB, CONNECTICUT.

COLLAR-BUTTON.

1,348,450.

Specification of Letters Patent. Patented Aug. 3, 1920.

Application filed April 11, 1919. Serial No. 289,233.

To all whom it may concern:

Be it known that I, PIERRE A. RONTEY, a citizen of the United States, residing at Cos Cob, in the county of Fairfield and State of Connecticut, have invented certain new and useful Improvements in Collar-Buttons, of which the following is a specification.

My invention relates to new and useful improvements in collar buttons and an important object thereof resides in the provision of a device which will facilitate the buttoning of a collar.

Another object of my invention resides in the provision of a device of the above mentioned character, including means which may be normally retained within the button, or may if desired be extended upon opposite sides of the button to retain the same within its respective button holes.

Other objects and advantages of my invention will become apparent during the course of the following description.

In the accompanying drawings forming a part of the description and wherein like numerals are employed to designate like parts throughout the same,

Figure 1 is a front elevation of the invention.

Fig. 2 is a side elevation of the same.

Fig. 3 is a front elevation of the invention with the rod thereof extended and arranged at right angle to the shank of the button.

Fig. 4 is a vertical section through the invention, and

Fig. 5 is a transverse section through the shank of the button and taken on the line 5-5 of Fig. 1.

In the drawings wherein is shown a preferred embodiment of my invention, the numeral 6 designates in general a collar button pressed out of a single piece of material to provide a base 7, an elliptical shank 8, and a head 9 which is in the form of a cup shaped socket. The upper edge of the socket 9 is provided with a pair of upstanding oppositely disposed ears 10, each of which is provided with a perforation 11.

A ball shaped member 12 is provided with a pair of oppositely disposed pintles 13, by which the ball is pivotally mounted upon the socket, by the pintles engaging with the perforations 11 in the ears. As clearly shown in Fig. 1, approximately one third of the ball 12 is received in the socket 9 for a purpose which will hereinafter appear.

This ball 12 is provided with a diametrically extending bore 14 which is provided in the relative lower portion of the ball and normally extends in a vertical plane with relation to the button. The relative upper portion of the bore 14 is restricted as at 15, whereby a rod 16 is slidably mounted in the restricted portion 15 of the bore. Both ends of this rod are enlarged to form an abutment 17 and a head 18, so that the rod cannot become detached from the ball 12. When the rod 16 is moved outwardly of the ball to its outermost extended position, it will be seen that the abutment 17 will abut with the restricted walls of the bore 14 and thereby prevent displacement of the rod with the head. When the rod is in its normal position and the lower end thereof is arranged within the shank 8, the head 18 of the rod will abut with the outer surface of the ball to prevent further downward movement of the rod and consequently will retain the rod within the ball.

To use the button, it is passed through the front button holes of a collar band attached to shirt, then the head 18 is grasped and moved outwardly to extend the rod 16 from the ball 12. One button hole in one end of the collar is then threaded over the head 18 and then on to the rod 16. When this is accomplished, it will be understood that the rod 16 extends at an angle to the shank 8, and by actuating the rod to draw the collar button hole toward the head of the button it will be seen that the end of the collar will slide down the rod 16 until it abuts with the ball 12. As the other hand of the operator is free, he may press upon the free end of the collar so that the button hole therein is forced over the ball 12, socket 9 and then brought upon the shank of the collar button in its proper position. The other end of the collar is placed upon the shank 8 in a similar manner. Then, the rod 16 is actuated to slide it back through the bore 14, the restricted portion 15 thereof, and then into the shank of the button. If, after the collar has been attached to the button, it is desired to provide an additional retaining means so that the free ends of the collar will not become disengaged with the head of the button, the ball 12 may be swung upon its pivot so that the extended rod 16 is arranged at right angles to the shank of the button, as more clearly shown in Fig. 3 of 110

the drawings. The rod 16 may then be actuated or moved back through the bore 14 so that each end of the rod 16 extends beyond opposite sides of the socket 9. When the rod 5 is in this position, it will be clearly seen that an additional abutment is provided so that it is practically impossible for the free ends of the collar to become detached from the button.

10 The foregoing description and the drawings have reference to what may be considered the preferred, or approved, form of invention. It is to be understood that I may make such changes in constructions and 15 arrangement, and combination of parts, materials, dimensions, etc., as may prove expedient and fall within the scope of the appended claims.

Having thus fully described my invention, 20 what I claim as new and desire to secure by Letters Patent, is:

1. A collar button comprising a shank, a member pivotally mounted in the shank or said collar button and provided with a bore 25 therethrough having a restricted portion, a rod slidably mounted in said bore, and means on each end of said rod for engagement with

said restricted portion to prevent disengagement of the rod with said pivoted member.

2. The combination with a collar button 30 having a socket on one end thereof, a member pivotally mounted in said socket, and a rod slidable through said member and capable of extension upon opposite sides thereof. 35

3. The combination with a collar button having a socket on one end thereof, of a ball pivotally mounted upon said collar button so that approximately one third of said ball is disposed in said socket, and a rod diametrically slidable through said ball. 40

4. The combination with a collar button having a socket on one end thereof and a hollow shank, of a member pivotally mounted in said socket, and a rod slidably mounted in said member whereby said rod may be received in said hollow shank or may be extended upon opposite sides of said member. 45

In testimony whereof I affix my signature in presence of two witnesses.

PIERRE A. RONTEY.
